POWDER ATOMIZER CONTAINER

Mauricio Jakab, New York, N. Y.

Application November 2, 1955, Serial No. 544,422

11 Claims. (Cl. 43—146)

This invention relates to a combined powder container and dispenser and, more particularly, to a powder dispensing box of the "squeeze" type.

In the use of various powders such as toilet powders and insecticides or other dusting powders and the like, it is frequently desirable to provide a convenient method to spray out the powder in the form of a fine cloud of dust. In this way it is possible to obtain the full value of a finely divided powder, since in the fine cloud each minute particle is substantially separated from each other particle. A maximum covering effect may thus be obtained from a minimum use of material and, in addition, the powder may be blown into ordinarily inaccessible places.

It is a prime object of the present invention to provide a powder box which is adapted to eject powder in the form of a fine cloud.

It is another object of the invention to provide a combined powder box and powder sprayer whereby a powder may be stored and then ejected, when used, in the form of a fine cloud.

A further object of the invention is to provide a combined powder box and sprayer with an improved form of discharge and diffuser nozzle.

Still another object of the invention is to provide a combined powder box and powder sprayer with an annular closure strip serving as an advertising medium.

It is further proposed to produce a combined powder box and powder sprayer that is simple in construction and that can be manufactured and sold at a reasonable cost.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 is a perspective view of a combined powder box and powder sprayer embodying the invention.

Fig. 2 is an enlarged side elevational view thereof shown in operative position between the fingers of the user.

Fig. 3 is a vertical sectional view taken on the plane of the line 3—3 of Fig. 1.

Fig. 4 is a fragmentary vertical sectional view taken on the plane of the line 4—4 of Fig. 3, the parts being shown in closed condition.

Fig. 5 is a horizontal sectional view taken on the plane of the line 5—5 of Fig. 3, the parts being shown in open condition for spraying.

Fig. 6 is a perspective detail view of the discharge nozzle.

Fig. 7 is a fragmentary vertical sectional view similar to Fig. 3 but showing a modification of the invention.

Referring to the figures of the drawing in detail, the combined powder box and powder sprayer made in accordance with the invention comprises a body section

2

10 and a cover section 11 preferably formed of suitable plastic material. The body section 10 is hollow and cylindrical in cross section and may be of any desired diameter and any desired length to constitute the height of the box, these dimensions determining the capacity of the box as will be understood. The body section includes a thin flexible circular disc 12 constituting the bottom wall of the box and which is provided with integral upstanding spaced inner and outer flanges 13 and 13', respectively, formed thicker than the bottom wall and serving as part of the side wall of the box. A thin peripheral flange 14 extends radially around the bottom end of the upstanding flange 13'. The top of the body section is open.

The cover section 11 includes a thin rigid or non-flexible circular disc 15 constituting the top wall of the box and is provided with a depending flange 16 formed thicker than the top wall. A thin peripheral flange 18 extends radially around the top end of the depending flange 16. The internal diameter of the depending flange 16 is slightly greater than the external diameter of the upstanding flange 13 of the body section so that the cover section loosely fits over the open end of the body section, with its flange 16 fitted in the space between the flanges 13 and 13', and its flange 18 seating on flange 13' of the body section 10, thereby removably closing the open top end of the body section to permit filling of the body section with powder.

The discs 12 and 15 constituting the bottom and top walls of the powder box are formed concavo-convex, with the convex side outermost and with the opposed centers of the two walls farthest apart.

A cutout 19 is formed in the upstanding inner flange 13 of the body section 10, which cutout is rectangular in shape and extends from a point remote from the disc 12, forming a ledge 20 adjacent the disc, to and intersecting the upper edge of the flange 13 as shown in Fig. 3. An opening 17 is formed in outer flange 13' in line with the cutout 19. A discharge nozzle device 21 is mounted in the cutout 19. This nozzle device is formed of suitable plastic material and as shown in Fig. 6 comprises a tubular member 22 extending radially from an integrally formed backing plate 23, inwardly to the interior of the body section 10. The backing plate 23 is slightly curved to conform to the curvature of flange 13 and is formed with a lower offset portion 24 disposed outwardly of the flange 13 and seated on the peripheral flange 14 of the body section 10. The dimensions of the backing plate 23 are slightly larger than the dimensions of the cutout 19 so that the side edges of the base plate engage the inner surface of the flange 13 on both sides of the cutout, with the bottom offset portion 24 thereof disposed between flanges 13 and 13' and engaging the outer surface of said flange 13, thereby closing the cutout 19, with the tubular member 22 seated on the ledge 20. The nozzle device may be secured in position by applying a suitable adhesive on the flange engaging portions thereof. A pin hole 25 is formed in the backing plate 23 centrally of the tubular member 22 in line with opening 17 in flange 13' and the tubular member 22 is formed with spaced ribs 26 extending the length thereof around said hole 25.

A thin annular band or ring 27 of plastic material encircles the outer flange 13' of the body section 10 and forms part of the side wall of the box. The band or ring seats on the flange 14 of body section 10 and is turnable around the flange 13' in the direction of the arrows on Fig. 1 and is guided in its movements by flanges 14 and 18. The band is formed with a pin hole 28 adapted to be moved into register with the larger opening 17 in the flange 13' of the body section 10 and with the pin hole 25 in the nozzle device 21. The band may have

suitable advertising indicia thereon, such as indicated at 29.

If desired, the top wall 15 of the box may have suitable decorative effects such as indicated at 30.

In use, the outer band 27 is turned until the hole 28 therein registers with the opening 17 in the outer flange 13' of the section 10 and with the aligned hole 25 in the nozzle device. The box is then held in the hand between the thumb and forefinger as shown in Fig. 2 and the bottom wall squeezed toward the top wall whereupon the internal area or capacity of the box is reduced and an outward pressure or flow of air within the box is exerted which finds exit through the tubular member 22 where it is further diffused by the ribs 26. From the tubular member 22 the powder is forced through the hole 25 in plate 23 and through the aligned opening 17 in flange 13' and hole 28 in the outer band 27 in the form of a spray as shown in Fig. 1.

In Fig. 7, a modified form of discharge nozzle device and mounting therefor are shown. In this form, the tubular member 22' is formed with ribs 26' arcuately shaped in cross section with sharp points 31, the pointed ends of the ribs being arranged in overlapping concentric relation so that the powder passing through the tubular member is deflected from one rib to another and is effectively broken up into particles.

The cutout 19' is formed with an enlarged upper end having its upper end edges 33 curved. The curved edges 33 facilitate entrance into the cutout of the nozzle device, and the cutout is enlarged to accommodate laterally extending lugs 34 on the backing plate 23' so that when the nozzle device is inserted downwardly into the cutout 19', the lugs 34 will cam against the edges of the cutout and wedge the nozzle device in position against displacement.

In all other respects, the form of the invention shown in Fig. 7 is similar to the form shown in Figs. 1 to 6, inclusive, and similar reference numerals are used to indicate similar parts.

It will thus be seen that a simple and economically manufactured box has been provided for the purpose of containing powder of any kind and of dispensing the same in the manner of a bellows, the ribs, in the tubular member serving to break up the particles of powder into a fine dust. The box may be made of any height or diameter depending upon the use to which it is to be put.

While I have illustrated and described the preferred embodiments of my invention, it is to be understood that I do not limit myself to the precise constructions herein disclosed and that various changes and modifications may be made within the scope of the invention as defined in the appended claims.

Having thus described my invention, What I claim as new, and desire to secure by United States Letters Patent is:

1. A box for dispensing powders, insecticides or the like comprising a cylindrical body section having a flexible bottom wall, an open top and spaced inner and outer flanges around the bottom wall, a cover section for the open top of said body section including a rigid top wall and a depending flange in the space between said inner and outer flanges, a perforated discharge nozzle device mounted in the upstanding inner flange of the body section below said depending flange, said outer flange having an opening in line with the perforation in said nozzle device, and an annular band encircling said outer flange of the body section and turnable therearound, said band having a hole therein adapted to be moved into register with the opening in the outer flange.

2. A box for dispensing powders, insecticides or the like comprising a cylindrical body section having a flexible bottom wall, an open top and upstanding spaced inner and outer flanges around the bottom wall, a cover section for the open top of said body section including a rigid top wall and a depending flange in the space be-

tween said inner and outer flanges, said upstanding inner flange on the body section having a cutout therein, a perforated tubular discharge nozzle device mounted in said cutout, said outer flange having an opening in line with the perforation in said nozzle device, and an annular band encircling said outer flange of the body section and turnable therearound, said band having a hole therein adapted to be moved into register with the opening in the outer flange.

3. A box for dispensing powders, insecticides or the like comprising a cylindrical body section having a flexible bottom wall, an open top and upstanding spaced inner and outer flanges around the bottom wall, a cover section for the open top of said body section including a rigid top wall and a depending flange in the space between said inner and outer flanges, said upstanding inner flange having a cutout therein, a discharge nozzle device mounted in the cutout in said upstanding inner flange, below said depending flange, said nozzle device including a backing plate and a tubular member extending radially of said backing plate into the interior of the body section, said backing plate having a hole centrally of the tubular member, said outer flange having an opening in line with the hole in said backing plate, and an annular band encircling said outer flange of the body section and turnable therearound, said band having a hole therein adapted to be moved into register with the opening in the outer flange of the body section.

4. A box for dispensing powders, insecticides or the like comprising a cylindrical body section having a flexible bottom wall, an open top and upstanding spaced inner and outer flanges around the bottom wall, a cover section for the open top of said body section including a rigid top wall and a depending flange in the space between said inner and outer flanges, said upstanding inner flange having a cutout therein, a discharge nozzle device mounted in the cutout in said inner upstanding flange, said nozzle device including a backing plate and a tubular member extending radially of said backing plate into the interior of the body section, said backing plate having a hole centrally of the tubular member, said outer flange having an opening in line with the hole in said backing plate, opposed peripheral flanges on said top and bottom walls, and an annular band encircling said outer flange of the body section between said peripheral flanges and turnable around said outer flange, said band having a hole therein adapted to be moved into register with the opening in the outer flange of the body section.

5. A box for dispensing powders, insecticides or the like comprising a cylindrical body section having a flexible bottom wall, an open top and upstanding spaced inner and outer flanges around the bottom wall, a cover section for the open top of said body section including a rigid top wall and a depending flange in the space between said inner and outer flanges, said upstanding inner flange having a cutout therein, a discharge nozzle device mounted in the cutout in said upstanding inner flange, said nozzle device including a backing plate and a tubular member extending radially of said backing plate into the interior of the body section, said backing plate having a hole centrally of the tubular member, said outer flange having an opening in line with the hole in said backing plate, an annular band encircling said outer flange of the body section and turnable therearound, said band having a hole therein adapted to be moved into register with the opening in the outer flange of the body section, and means in said tubular member for pulverizing the powder passing therethrough.

6. A box for dispensing powders, insecticides or the like comprising a cylindrical body section having a flexible bottom wall, an open top and upstanding spaced inner and outer flanges around the bottom wall, a cover section for the open top of said body section, including a rigid top wall and a depending flange in the space between said inner and outer flanges, said upstanding inner

flange on the body section having a perforated tubular discharge nozzle device mounted in said inner flange, said discharge nozzle having an opening in line with the perforation in said nozzle device, an annular band encircling said outer flange of the body section and turnable therearound, said band having a hole therein adapted to be moved into register with the opening in the outer flange, and spaced ribs in the tubular discharge nozzle for pulverizing the powder passing therethrough.

7. A box for dispensing powders, insecticides or the like comprising a cylindrical body section having a flexible bottom wall, an open top and upstanding spaced inner and outer flanges around the body section, a cover section for the open top of said body section including a rigid top wall and a depending flange in the space between said inner and outer flanges said upstanding inner flange having a cutout therein, a discharge nozzle device mounted in the cutout in said upstanding flange, said nozzle device including a backing plate and a tubular member extending radially of said backing plate into the interior of the body section, said backing plate having a hole centrally of the tubular member, said outer flange having an opening in line with the hole in said backing plate, an annular band encircling said outer flange of the body section and turnable therearound, said band having a hole therein adapted to be moved into register with the opening in the outer flange of the body section.

8. A box for dispensing powders, insecticides or the like comprising a cylindrical body section having a flexible bottom wall, an open top and upstanding spaced inner and outer flanges around the bottom wall, a cover section for the open top of said body section including a rigid top wall and a depending flange in the space between said flanges, the upstanding inner flange having a cutout therein, a discharge nozzle device insertable in the cutout in said upstanding inner flange, said nozzle device including a backing plate and a tubular member extending radially of said backing plate into the interior of the body section, said backing plate having a hole centrally of the tubular member, said outer flange having an opening in line with the hole in said backing plate, an annular band encircling said outer flange of the body section and turnable therearound, said band having a hole therein adapted to be moved into register with the opening in the outer flange of the body section, said backing plate having an offset portion interlocked with the upstanding inner flange of the body section below said cutout.

9. A box for dispensing powders, insecticides or the like comprising a cylindrical body section having a concavo-convex flexible bottom wall, an open top and upstanding spaced inner and outer flanges around the bottom wall, a cover section for the open top of said body section including a concavo-convex rigid top wall and a depending flange in the space between said inner and outer flanges, said upstanding inner flange having a cutout therein forming a ledge on the upstanding inner flange below the cutout, a discharge nozzle device mounted in the cutout in said upstanding inner flange, said nozzle device including a backing plate and a tubular member extending radially of said backing plate into the

interior of the body section, said tubular member being seated on said ledge, said backing plate having a hole centrally of the tubular member, said outer flange having an opening in line with the hole in said backing plate, an annular band encircling said outer flange of the body section and turnable therearound, said band having a hole therein adapted to be moved into register with the opening in the outer flange of the body section, said backing plate having an offset portion interlocked with the upstanding inner flange of the body section below said cutout.

10. A box for dispensing powders, insecticides or the like comprising a cylindrical body section having a flexible bottom wall, an open top and upstanding spaced inner and outer flanges around the bottom wall, a cover section for the open top of said body section, including a rigid top wall and a depending flange in the space between said inner and outer flanges, said upstanding inner flange on the body section having a cutout, a perforated tubular discharge nozzle device insertable in said cutout, said outer flange having an opening in line with the perforation in said nozzle device, an annular band encircling said outer flange of the body section and turnable therearound, said band having a hole therein adapted to be moved into register with the opening in the outer flange, and spaced ribs in the tubular discharge nozzle for pulverizing powder passing therethrough, said ribs being arcuate-shaped in cross section with pointed ends, the pointed ends of the ribs being arranged in overlapping concentric relation.

11. A box for dispensing powders, insecticides or the like comprising a cylindrical body section having a flexible bottom wall, an open top and upstanding spaced inner and outer flanges around the bottom wall, a cover section for the open top of said body section, including a rigid top wall and a depending flange in the space between said inner and outer flanges, said upstanding inner flange on the body section having a cutout intersecting the top edge thereof, the top end of said cutout being enlarged with curved top end edges, a discharge nozzle device insertable in the cutout in said upstanding inner flange, said nozzle device including a backing plate and a tubular member extending radially of said backing plate into the interior of the body section, said backing plate having laterally extending lugs slidable over the curved top end edges of the cutout and coacting with the edges of the enlarged top end of the cutout for wedging the nozzle device against displacement, said backing plate having a hole centrally of the tubular member, said depending flange having an opening in line with the hole in said backing plate, and an annular band encircling said outer flange of the body section and turnable therearound, said band having a hole therein adapted to be moved into register with the opening in said outer flange.
